PATRICK E. McGINTY

BY

INVENTOR:

Fred L. Fraenzel,

ATTORNEY

UNITED STATES PATENT OFFICE.

PATRICK E. MCGINTY, OF NEWARK, NEW JERSEY, ASSIGNOR TO WILLIAM H. COLEMAN, OF NEWARK, NEW JERSEY.

NAIL-HOLDER FOR HAMMERS.

SPECIFICATION forming part of Letters Patent No. 701,076, dated May 27, 1902.

Application filed November 21, 1901. Serial No. 83,086. (No model.)

To all whom it may concern:

Be it known that I, PATRICK E. MCGINTY, a citizen of the United States, residing at Newark, in the county of Essex and State of New Jersey, have invented certain new and useful Improvements in Nail-Holders for Hammers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in hammers; and the invention relates more particularly to a novel construction of nail-holding attachment or device which is to be applied to the hammer of the ordinary construction now in use, the said attachment or device being made to receive the head of a nail and retaining it in the proper position for lightly driving the sharp or pointed end of the nail into the wood before finally driving the nail entirely into the wood by means of the driving-head of the hammer in the usual manner.

The invention has for its principal objects to provide a simple and a cheaply-constructed nail-holding attachment or device which can be readily applied to any known form and construction of hammer, the device or attachment having this special advantage that a nail can be held in the proper position prior to driving the same home, and the hammer and nail can both be manipulated at one time and in such places where a carpenter cannot use both hands, as heretofore, one hand for holding the nail and the other hand for swinging the hammer.

The said invention therefore consists in the novel construction of nail-holding device or attachment hereinafter more fully set forth; and, furthermore, this invention consists in the several novel arrangements and combinations of the various parts, all of which will be described in detail in the accompanying specification and then finally embodied in the clauses of the claim.

The invention is clearly illustrated in the accompanying drawings, in which—

Figure 1 is a side view of a hammer and a nail-holding device or attachment secured thereto, representing a nail held in its proper position ready to be lightly driven into the wood by means of the hammer. Fig. 2 is an end view of the driving portion of the hammer with a face view of the nail-holding device or attachment embodying the principles of this invention. Fig. 3 is a longitudinal vertical section of the driving portion of the hammer, a portion of the handle to which said head is attached, and the said nail-holding attachment or device, the said view illustrating one manner of securing the said nail-holding attachment or device in its operative position. Fig. 4 is a face view, Fig. 5 a side view, and Fig. 6 a rear view, of the nail-holding attachment or device in its detached position from the hammer, the said views showing the said device on an enlarged scale. Fig. 7 is an end view of the driving-head of a hammer and a nail-holding device or attachment of a slightly-modified form of construction, but still embodying the principles of this invention; and Fig. 8 is a longitudinal vertical section of the said parts represented in said Fig. 7, the said view also representing the said parts in their operative position on the end of the handle.

Similar characters of reference are employed in all of the said above-described views to indicate corresponding parts.

In the said drawings the reference character 1 indicates the handle, and 2 the hammer-head, the latter being provided with the usual form of driving-shank 3 and an eye or receiving member 4, in which the end 5 of the handle is secured in the usual manner. The said nail-holding device or attachment is indicated by the reference character 6, and it consists, essentially, of a main body or face-plate 7, which is made with an opening or slot 8, extending from the one side of the said face-plate to a point near the opposite side thereof, as illustrated more particularly in Figs. 2, 4, and 7 of the drawings. The said slot or opening 8 is made much wider at the bottom of the said face-plate 7, the said enlarged or wider portion, which is indicated by the reference character 9, being formed by a pair of shoulders 10, which when a nail 11 is in-

serted in the slot or opening are fitted directly over the marginal edges of the head of the said nail, and thereby hold or retain the said nail in its proper position in the said device 5 or attachment 6, as will be clearly understood. In order that the said nail 11 may be more securely retained in its fixed position in the said slot or opening 8, the said slot or opening has its marginal edges 12 and 13 10 made to extend in a downward direction toward the lower edge 14 of the said face-plate 7, as shown, the said edges being arranged at different angles, so that said edges, if prolonged, would meet, whereby the entrance to said slot or opening 8 is much wider than the end 15 of the said slot or opening and whereby when the nail is inserted the said end 15 will securely engage the body of the nail just below its head and will retain 15 the said nail in a fixed position in alignment with the central longitudinal axis of the driving-shank 3 for driving the sharp end of the nail into the wood. After the nail has been fixed in the wood a movement of the hammer 20 in a lateral direction will disengage the said holding device or attachment 6 from the nail. To securely fix the said nail-holding device or attachment in its operative position to the hammer-head 2, the means illustrated more 25 particularly in Figs. 1 to 6, inclusive, is preferably employed. This means consists, essentially, of a rearwardly-extending portion or member 16, which is provided with a forwardly-extending plate or holding-arm 17, as 30 illustrated. This plate or arm 17 is of such thickness and width that it can be securely arranged against the inner surface of the eye or receiving member 4 of the hammer-head, as illustrated in Fig. 3 of the drawings, and 35 when the end portion 5 of the handle is driven into said eye 4 then the said plate or arm 17 will be securely wedged in its operative position between the said end portion of the handle and a portion of the inner surface of the 40 said eye 4, substantially as illustrated. Of course it will be understood that the said opening or slot 8 may be differently arranged in the said face-plate 7, and the complete nail-holding device or attachment 6 may be 45 secured at any side of the hammer-head, if desired.

Instead of providing the nail-holding device or attachment with the holding-arm or plate 17, the said arm or plate and the rearwardly-extending portion or member 16 may be dispensed with, in which case the said device is made as indicated in Figs. 7 and 8 of the drawings. In that case the said face-plate 7 is made with one or more perforations 55 or holes 18, the eye portion of the hammer-head being provided with correspondingly-arranged holes or perforations 19, as illustrated in said Fig. 8, and in which can be arranged screws or pins 20 for securely fixing 60 the said nail-holding device or attachment in its operative position.

From the above description of the present

invention it will be obvious that a simply-constructed and efficient device or attachment for the purposes stated has been produced 70 which can be easily and quickly applied in position on any well-known construction and form of hammer.

I am aware that some changes may be made in the arrangements and combinations of the 75 various parts of the device, as well as in the details of the construction thereof. Hence I do not limit this invention to the exact arrangements and combinations of the parts as described in the previous specification and as 80 illustrated in the accompanying drawings, nor do I confine myself to the exact details of the construction thereof.

Having thus described my invention, what I claim is—

1. A device for holding nails to hammer-heads, comprising, a main body or face-plate, a rearwardly-extending member 16 on said body and a holding-arm 17 on said member 16 adapted to be arranged in the receiving-eye 90 of the hammer-head and held between one of the inner surfaces of said eye and a portion of the inserted hammer-handle, for securing said device in position against the hammer-head, the said main body or face-plate being provided with a nail-receiving opening, said opening being wider at the bottom than at its outer edges for retaining a nail in position, substantially as and for the purposes set forth.

2. A device for holding nails to hammer-heads, comprising, a main body or face-plate, a rearwardly-extending member 16 on said body and a holding-arm 17 on said member 16 adapted to be arranged in the receiving-eye 100 of the hammer-head and held between one of the inner surfaces of said eye and a portion of the inserted hammer-handle, for securing said device in position against the hammer-head, the said main body or face-plate being provided with a nail-receiving opening, and a 105 pair of shoulders, said shoulders forming a wide opening for the reception of the head of the nail, and a narrow open portion in which the shank of the nail is fitted, substantially as and for the purposes set forth.

3. A device for holding nails to hammer-heads, comprising, a main body or face-plate, a rearwardly-extending member 16 on said main body and a holding-arm 17 on said member 16 adapted to be arranged in the receiving-eye 110 of the hammer-head and held between one of the inner surfaces of said eye and a portion of the inserted hammer-handle, for securing said device in position against the hammer-head, the said main body being provided with a nail-receiving opening having marginal edges 12 and 13 arranged at different inclinations to each other to provide a wide entrance for the nail and a narrow holding portion at the end of said opening, substantially as and for the purposes set forth.

4. A device for holding nails to hammer-heads, comprising, a main body or face-plate, a rearwardly-extending member 16 on said

main body and a holding-arm 17 on said member 16 adapted to be arranged in the receiving-eye of the hammer-head and held between one of the inner surfaces of said eye and a portion of the inserted hammer-handle, for securing said device in position against the hammer-head, the said main body being provided with a nail-receiving opening having marginal edges 12 and 13 arranged at different inclinations to each other to provide a wide entrance for the nail and a narrow holding portion at the end of said opening, and a pair of shoulders, forming a wide open portion for the reception of the head of the nail and a narrow open portion in which the shank of the nail is fitted, substantially as and for the purposes set forth.

5. A device for holding nails to hammer-heads, comprising, a main body or face-plate, means for securing said main body or face-plate in position against a portion of the hammer-head, the said main body being provided with a nail-receiving opening having a pair of marginal edges arranged at different inclinations to each other to provide a wide entrance for the nail and a narrow holding portion at the end of said opening, but the angles of inclination of said marginal edges both being in an upward direction toward the hammer-head, when said nail-holding device is in position against the said hammer-head, whereby the narrow nail-holding portion is lower than the wide receiving-entrance to hold the in-

serted nail against accidental lateral displacement, substantially as and for the purposes 35 set forth.

6. A device for holding nails to hammer-heads, comprising, a main body or face-plate, means for securing said main body or face-plate in position against a portion of the hammer-head, the said main body being provided with a nail-receiving opening having a pair of marginal edges arranged at different inclinations to each other to provide a wide entrance for the nail and a narrow holding portion at the end of said opening, but the angles of inclination of said marginal edges being both in an upward direction toward the hammer-head, when said nail-holding device is in position against the said hammer-head, 50 whereby the narrow nail-holding portion is lower than the wide receiving-entrance to hold the inserted nail against accidental lateral displacement, and a pair of correspondingly-inclining shoulders forming a wide open 55 portion for the reception of the head of the nail, substantially as and for the purposes set forth.

In testimony that I claim the invention set forth above I have hereunto set my hand this 19th day of November, 1901.

PATRICK E. MCGINTY.
